United States Patent Office.

JOHN TESSEYMAN, OF DAYTON, OHIO.

Letters Patent No. 63,673, dated April 9, 1867.

IMPROVEMENT IN PLANING MACHINES.

The Schedule referred to in these Letters Patent and making part of the same.

TO WHOM IT MAY CONCERN:

Be it known that I, JOHN TESSEYMAN, of Dayton, Montgomery county, Ohio, have invented a new and useful Adjustable Planing-Head; and I hereby declare the following to be a full, clear, and exact description thereof, reference being had to the accompanying drawings, making part of this specification.

My improvement is especially designed for what are known as rotating disk planers, in which the path of the cutting edge is coincident with a plane, or the periphery of a very obtuse cone, parallel or tangential to the surface of the board or plank to be dressed; and my invention consists in a construction of tool or bit-holder, which enables one or more cutters to be set out from or in towards the axis of rotation, and yet preserve the most effective angle of presentation in respect to the wood, so as to have in every position a paring or shaving rather than an excavating or tearing cut.

Figure 1 is a perspective view of a planing head embodying my invention, the bit-holder on one side being detached.

Figure 2 is a side elevation of said head.

Figure 3 is an axial section through my adjustable bit-holder.

A is the shaft, and B the T-head of a disk planer, each arm, b, of which has a cylindrical termination, C C', to receive and hold the tool-holder, which holder being precisely similar in each, the same description and letters will apply to both. The cylindrical termination is traversed at right angles to the shaft A by the screw-threaded shank or bolt D, having a nut, E, and a flat head, F, slotted f, to receive the bit G. H is a washer, traversed axially by an orifice fitting and adapted to receive the head F. The face or advancing end h of the washer is grooved, I, to receive the rear inner edge of the bit, and sloped obliquely in the same direction as said groove. The rear end of said washer has radial serrations, J, which fit similar serrations K in the head. The inner rear edge of the bit being sunk the most deeply into the sloping face of the washer, and its cutting edge consequently inclining rearward as it approaches the axis of rotation, the bit is made to act with a shaving or paring rather than a tearing cut, and when set out from the axis, as is often required to be done in order to have a leading cut over the other bit, the shaving angle and action are still preserved, which they could not be if the sloping face h was immovable on the head, as in the customary planers. The bit is easily set out or in by simply slackening the nut E and turning of the washer H, when the nut, being screwed fast, co-acts with the serrations J K to retain the holder securely in place.

I claim herein as new, and of my invention—

1. The provision in a planing head of obliquely faced washer or tool holder H, adjustable about an axis tangential, or nearly so, to the path of the bit, substantially as set forth.
2. A tool holder for a disk or conical planer, consisting of the oblique-faced and serrated washer H, slotted bolt D F f, nut E, and serrated head B, for the purpose set forth.

In testimony of which invention I hereunto set my hand.

JOHN TESSEYMAN.
